DES. 2189

Laporte Hubbell of Bristol, Conn.

Letter Patent No. 2189 Dated Oct 10 1865.

Design for the movement frame of a clock.

The schedule referred to in these Letters Patent and making part of the same.

It will be seen it may contain:

Bent knoweth that Laporte Hubbell of Bristol, in the County of Hartford and State of Connecticut, have devised and produced a new and original design for Thirty Day Marine Clock movement, and do hereby declare the following when taken in connection with the accompanying drawings and the letters of reference marked thereon, to be a full, clear and exact description of the same, and which said drawings constitute part of this specification, and represent a front view of any new design.

My design relates to the form of the plate which supports the operative parts of the movement, the object being a more graceful and artistic appearance than that given in the ordinary square frame.

The frame A, is formed as seen in the drawings so as to place the wheels nearly in a perpendicular line, one above the other and give to the whole an evenly balanced appearance.

What I claim as my production and desire to secure by Letters Patent is,

The design for clock frame or plate shown and described.
